PIVOTED SWEEP ARM BENDER WITH
WORK-CLAMPING JAW AND NESTED
SLEEVES ON FULCRUM

Harvey W. English, Portland, Oreg.

Application October 26, 1945, Serial No. 624,741

3 Claims. (Cl. 153—46)

1

This invention relates to bending devices, and more particularly to an apparatus for bending bars to form rings, U-bolts, or the like.

A main object of the invention is to provide a novel and improved bending apparatus which is very simple in structure and which is extremely easy to operate.

A further object of the invention is to provide an improved bending device for bending bars into ring shape or to form U-bolts, said device being extremely simple in construction and being very efficient in operation, and being further provided with readily interchangeable means for adjusting the device to bend bars to a curvature of desired radius.

Further objects and advantages of the invention will appear from the following description and claims and from the accompanying drawings, wherein:

Figure 1 is a top plan view of a bending device constructed in accordance with this invention.

Figure 2 is a side elevational view of the bending device of Figure 1.

Figure 3 is a top plan view of the main body portion of a movable die supporting member employed in the device of Figure 1.

Figure 4 is an end elevational view of the die supporting member of Figure 3.

Figure 5 is an end elevational view of the supporting base member employed in the bending device of Figure 1.

Figure 6 is a side elevational view of a movable jaw member employed in the device of Figure 1.

Figure 7 is an end elevational view of the jaw member of Figure 6.

Figure 8 is an end elevational view of a die carrier employed with the die supporting member of Figure 3.

Figure 9 is a side elevational view of a stationary die supporting member employed in the device of Figure 1.

Figure 10 is a side elevational view of a U-bolt gauge member employed with the device of Figure 1.

Figure 11 is a top plan view of the U-bolt gauge device of Figure 10.

Figure 12 is a side elevational view of a removable stationary die employed with the die supporting member of Figure 9.

Referring to the drawings, 11 designates a supporting base member for the bending apparatus. Member 11 is adapted to be rigidly secured to an appropriate stationary support, as, for example, a bench vise mounted on a shop bench. Member 11 is formed with a depending longitudinally extend-

2

ing central portion 12 adapted to be received between the jaws of a bench vise or similar clamping device. Member 11 is further formed with a horizontal table portion 13 and a pair of lug elements 14 and 15 formed to define a longitudinal dovetailed channel 16. Member 11 is also formed with a vertical internally threaded bore 17 whose axis lies in the central longitudinal vertical plane of channel 16.

Threadedly received in bore 17 is the lower threaded end 18 of a die supporting member 19, shown in Figure 9. Member 19 comprises a vertical shank portion or fulcrum member 20 and a horizontal shaft member 21. The lower portion 15 of shank 20 is formed with a bearing portion 22 and a laterally projecting rib element 23. The upper portion of shank 20 is formed with a bearing portion 24 and a peripheral groove 25, the top end of the shank 20 being tapered to a point 26.

Pivotedly secured to member 19 at the respective bearing surfaces 22 and 24 is a movable die supporting member 27 comprising a main body portion 28, shown in Figures 3 and 4, having hinged thereto a movable top member 29 by a horizontal hinge pin 30. Top member 29 is adapted to be rotatively engaged with bearing surface 24 and to be releasably secured in operative position by a latch member 31 which is biased by a spring 32 to an interlocking relationship with groove 25. The main body portion 28 of movable die supporting member 27 is secured in position with respect to table 13 by the overlying rib element 23 carried by member 19.

Movable die supporting member 27 is formed with a horizontal threaded bore 33 in which is threadedly engaged the end portion 34 of a handle member 35. Rotatively secured to the end of portion 34 is a C-shaped die carrier member 36. The lower arm of member 36 is grooved at 37, 37 to slidably interfit with longitudinal ribs 38, 38 formed in a longitudinal recess 39 provided for said lower arm in main body portion 28 of the movable die supporting member. The upper arm of member 36 is slidably received in a longitudinal recess 40 formed at the bottom of top member 29. Secured in vertical position between the upper and lower arms of member 36 by a bearing bolt 41 is a hardened roller member 42. Roller member 42 is formed with an arcuate groove 43 in its upper portion.

Slidably engaged with horizontal shaft 21 and dove-tailed lugs 14 and 15 is a movable jaw member 44. Jaw member 44 is formed with a longitudinal bore 45 which slidably fits shaft 21 and 55 with a dovetail lower longitudinal lug 46 adapted

to be slidably received between lugs 14 and 15. Jaw member 44 carries a hardened gripping jaw member 47 adapted to cooperate with shank 20 to grip a bar therebetween during the bending thereof. The opposite end of member 44 is formed with an annular flange 48 concentric with bore 45.

Threadedly engaged with the end portion 49 of member 18 is a feed handle 50 to which is secured a semi-cylindrical sleeve member 51 formed with an internal groove overlying and engaged with flange 48 so that rotation of handle 50 will advance or retract jaw member 44 with respect to shank 20 of die supporting member 19.

In operating the device a bar is positioned between jaw element 47 and shank 20 with the movable die supporting member 27 in the dotted position shown in Figure 1. Handle 50 is rotated so that the bar is tightly gripped between jaw element 47 and shank 20 and the handle 35 then axially rotated until roller 42 comes into contact with the bar at groove 43. Movable die supporting member 27 is then rotated counter-clockwise in a horizontal plane around member 19 by means of handle 35, as viewed in Figure 1, thus exerting bending force on the bar, with shank 20 acting as the fulcrum.

For bending the bar to a desired radius of curvature, a plurality of nested sleeve elements one of which is shown at 52 in Figure 12 may be provided. Each sleeve element is formed with a knurled gripping surface 53 and with a rounded bottom notch 54. The smallest sleeve has an inside diameter adapted to fit over shank 20 with its notch 54 receiving the adjacent portion of shaft 21. The next succeeding sleeve is formed with an inside diameter adapted to fit over the first sleeve with its notch 54 receiving shaft 21. By employing successive sleeves, any desired bending radius within a substantial range may be obtained.

The sleeves are all of the same length except the smallest sleeve which is shorter than the other sleeves by the thickness of rib element 23 upon which it is supported. The other sleeves encircle rib element 23 and rest on the adjacent horizontal surface of body portion 28.

Lug 14 of member 11 is formed with a pair of recesses 55, 55 adapted to receive the ends of the legs 56, 56 of a U-bolt gauge member 57, shown in Figure 10. Gauge member 57 is in the form of a U-bolt and carries an adjustable stop member 58 slidably supported by sleeves 59, 59 on the legs 56, 56 of the U-bolt, and which may be set by means of thumb screws 60, 60 at a desired position with respect to shank 20. As shown in Figure 10, the U-bolt carries a scale of gauge markings for setting the stop member at the proper distance for the particular length of U-bolt which it is desired to form in the bending device. As indicated in Figure 1, the end of the piece of bar stock 61 is initially placed in abutment with stop member 58 for securing the bar between the gripping jaws of the device in the correct position for a desired length of U-bolt.

To form a ring, a piece of bar stock is prepared of proper length for the ring desired and the bar is bent by a series of successive bending operations in the device until complete 360° bending is obtained.

While a specific embodiment of a bar bending

device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A bending device comprising a base adapted to be secured to a stationary support, jaw means mounted on said base, said jaw means comprising a stationary vertical fulcrum member formed with a horizontal shaft portion and a movable jaw slidably mounted on said horizontal shaft portion, cooperating guide means on said movable jaw and said base for guiding said movable jaw longitudinally with respect to said fulcrum member, jaw actuating means threadedly engaged with said horizontal shaft portion and engaging said movable jaw for moving said jaw with respect to said fulcrum member, a movable die supporting member pivotally secured to said fulcrum member for swinging movement in a horizontal plane, and a vertical roller carried by said movable die supporting member, said vertical roller being formed and arranged to exert bending pressure on a bar placed within said jaw means responsive to swinging movement of said movable die supporting member around said fulcrum member.

2. The structure of claim 1, and wherein a sleeve member is mounted on said fulcrum member, said sleeve member being formed with a lower notch adapted to receive said horizontal shaft portion.

3. A bending device, comprising a base, adapted to be secured to a stationary support, a vertical fulcrum fixed to said base, a horizontal arm secured to said fulcrum, a movable jaw slidably mounted on said arm, means mounting said jaw on said base for horizontal sliding movement on said base toward said fulcrum for gripping an article to be bent therebetween, a bending die pivoted on said fulcrum for bending an article thieraround, a plurality of nested sleeve members slidable onto and off of said fulcrum and each other to vary selectively the diameter of said fulcrum, said sleeves being formed with notches engageable with said arm for preventing relative rotation of said sleeves and fulcrum.
